LINE VOLTAGE REGULATOR

Edwin A. Link, Milwaukee, Wis., assignor to
R T & E Company, a corporation of Illinois

Application March 29, 1951, Serial No. 218,233

9 Claims. (Cl. 323—43.5)

1

This invention relates to regulators and more particularly to step type line voltage regulators operative to effect the automatic maintenance of line voltage fluctuations within certain predetermined and permissible limits.

The need for equipment of this type, particularly on long rural distribution lines, has existed for many years. Presently overloaded circuits supplying power at inadequate voltage levels have resulted from too conservative estimates, at the time of line installations, of future load growth and present-day load requirements. This common condition of overloaded circuits has emphasized the need for line voltage regulating equipment which would function automatically to raise the line voltage before any point along the line drops below a minimum voltage limit and lower the voltage before any point on the line rises above a maximum voltage limit.

Distribution line voltage limits, when referred to a 120 volt base, are generally regulated to hold the output voltage at full load between 124 and 127 volts and at light load between 120 and 124 volts; while the distribution line voltage limits, at the consumers' distribution transformers, have arbitrarily been established between 116 and 127 volts. From these figures, it will be apparent that there is a permissible line voltage fluctuation within the established predetermined limits.

The present invention provides a step type line voltage regulator which functions automatically to maintain the desired distribution line voltage within the predetermined limits by the operation of a control device which initiates a boost operation of the regulator when the voltage on the load side of the regulator drops to 120 volts or lower and which cuts out the boost operation of the regulator when the voltage on the load side of the regulator rises to 127 volts or higher.

The primary objects of the present invention resides in the provision of a new and improved step type line voltage regulator which operates automatically to maintain the load line voltage within predetermined and permissible limits.

Another object of the present invention resides in the provision of a new and improved step type line voltage regulator having a unitary core and coil structure with the coil including shunt and series windings arranged in fixed autotransformer relationship.

Another object of the present invention resides in the provision of a new and improved step type line voltage regulator having a unitary core and coil structure with the coil including

2

shunt, series and control windings arranged in fixed autotransformer relationship; with the control winding having a definite ratio with the load side voltage of the regulator.

5 Another object of the invention resides in the provision of a new and improved step type line voltage regulator having a control means responsive to the fluctuations in the load line voltage, beyond the predetermined and permissible limits, 10 to effect the operation of the regulator to maintain the load line voltage within the predetermined limits.

Another object of the invention resides in the provision of a new and improved step type line voltage regulator having control means responsive to the fluctuations in the load line voltage, a switch and switch operating means; with the switch operating means responding to operation of the control means to alter the switch position in accordance with the demands of the control means.

Another object of the invention resides in the provision of a new and improved step type line voltage regulator having a time delay means associated with a switch operating means; the time delay means serving to insure the change of the switch position only upon the persistence of the voltage change demand of the control device for a period of time not less than the time delay period of the time delay means.

Another object of the invention resides in the provision of a new and improved step type line voltage regulator having a switch operating means with rest and active positions and driving means responsive to control means for returning the switch operating means to its rest position upon the termination of any voltage change demand impressed upon the regulator by the control device.

40 Another object of the invention resides in the provision of a new and improved step type line voltage regulator including a control circuit provided with a limit switch which functions to terminate the active movement of the switch operating means to alter the position of the switch.

Another object of the invention resides in the provision of a new and improved step type line voltage regulator including a control circuit having a neutralizing switch which functions to terminate the return movement of the switch operating means when it reaches its rest position after the completion of a change of position of the switch in response to a voltage change demand impressed upon the regulator by the control means.

Other objects and advantages of the present invention will become apparent from the following description of the illustrative embodiment shown in the accompanying drawing.

The sole figure of the drawing is a schematic diagram of a line voltage regulator, constructed in accordance with the teachings of the present invention, showing in the illustrative embodiment of the invention a preferred combination of both mechanical and electrical means together with operating and control circuits.

The device chosen for illustrative purposes in the accompanying drawing comprises a single step line type voltage regulator. The operating elements of the regulator are contained in a sealed steel tank provided with pole mounting hangers so that the regulator may be mounted in a conventional manner on a line service pole. The control mechanism for the regulator is preferably contained in a control box, adapted for ready inspection, mounted either on the exterior wall of the enclosure tank or remote therefrom in case it is deemed more expedient to mount it near the base of the pole supporting the regulator; where it is readily accessible for inspection, adjustment or replacement without necessitating the climbing of the pole to gain access to the control box.

Referring to the schematic diagram, the illustrated step type line voltage regulator comprises generally a unitary core and coil structure 10, a switch 11, operative to selectively establish one of a plurality of connections between the power input line and the load line, a switch operating member 12, a driving means 13 for the switch operating member, a time delay mechanism 14 interposed between the driving means 13 and the switch operating member 12, and a control device 15 responsive to voltage fluctuations on the load line, beyond the predetermined and permissible limits, to initiate the operation of the driving means 13 to effect the shifting of the position of the switch 11 in accordance with the demands of the control device 15.

A detailed description of the main and control circuits of the device will be deferred until such time as the structure and functions of the several operating parts of the regulator have been discussed.

The unitary core and coil structure 10 is contained within a sealed steel tank and comprises a core 16 and a coil 17, preferably of the shell type. The coil 17 includes a plurality of windings comprising a shunt winding 18, a series winding 19 and a control winding 20 all of which are in fixed autotransformer relationship and so arranged that the ratio of transformation of the load side voltage of the regulator to the control winding voltage remains constant. A shield 21 preferably formed of copper and grounded with the coils 18, 19 and 20, through connection to the tank wall, is disposed between the shunt and control windings 18 and 20, respectively, to prevent surge voltages from being induced capacitively into the control circuit. The shield 21 serves a further purpose in that it provides safety protection to the lineman by preventing high voltages from occurring in the control circuit, should the unit become faulty.

The switch 11 and its associated mechanisms, the switch operating member 12, the driving means 13 and the time delay mechanism 14 comprise a unitary assembly unit arranged for mounting within the sealed steel tank and easily removable therefrom for the purpose of inspec-

tion, service or replacement. The switch 11 comprises an arm 22 mounted adjacent one end on a shaft 23 journaled for rocking movement in a suitable bearing member 24. A pair of oppositely projecting electrically connected contact elements 25 and 26 are mounted adjacent the free end of the movable switch arm 22. These contacts 25 and 26 serve respectively to connect line contacts 27 and 28 with coil contacts 29 and 30 dependent upon the position of the switch arm 22. A pin 31 positioned intermediate the ends of the arm 22 projects therefrom to provide an anchoring means for one end of a tension spring 32 which serves as a connector and actuating means between the switch arm 22 and the switch operating member 12.

The switch operating member 12 comprises an arm 33 having one end fixed to a shaft 34 through which motion is imparted to it. The shaft 34 is journaled for rotation in a pair of members 35 and 36. A pin 37 positioned adjacent the free end of the arm 33 projects therefrom to provide an anchoring means for the other end of the tension spring 32. It should be noted that the arrangement and positioning of the switch arm 22 and the operating arm 33 together with their fulcrum shafts 23 and 34 is such that movement of the switch operating arm 33 from its normal rest position, to effect the change of position of the switch arm 22 from one set of contacts to the other, results in the over-center movement of the tension spring 32 to cause the switch arm 22 to snap quickly from one set of contacts to the other. Suitable stops in the form of abutment members 38 are positioned in the path of travel of the arm 22 to arrest its motion with the contacts 25 and 26 bridging the gap between the stationary line and coil tap contacts.

The driving means 13, chosen for illustrative purposes in the drawing, comprises a reversible shaded pole motor 39 having a magnetic field winding 40, and a pair of pole shading windings 41 and 42, and an armature 43 mounted on an armature shaft 44 which carries a driving gear 45 for transmitting motion to the switch operating arm 33 through the medium of the time delay mechanism 14.

The time delay mechanism 14, as illustrated in the drawing, comprises a double reduction gear train including a couplet having a larger gear 46 meshing with and driven by the gear 45 on the armature shaft 44 and a smaller gear 47 meshing with and driving a gear 48 fixedly mounted on the shaft 34 on which the arm 33 on the switch operating member 12 is secured. The shaft 34 which carries the switch operating arm 33 also has secured to it a limit switch operating arm 49 and a neutralizing switch operating cam 50 which function in the control circuit, to be later described, which is responsive to the demands of the control device 15.

The control device 15 for the line voltage regulator is preferably contained in a control box adapted for selective mounting either on the exterior wall of the sealed steel tank containing the other parts of the regulator or it may be mounted as a unit remote from the tank, for example near the base of the pole on which the regulator is mounted, to render it more accessible for inspection, adjustment or replacement. In either instance, the electrical connections to and from the control device may be made by using any suitable plug-in connections. The control device 15, as illustrated in the drawing, comprises a contact making voltmeter 51, including a pri-

mary winding 52 and a secondary winding 53 connected to a heater 54 mounted on a shaft 55 to which is secured a pointer needle 56 having one end thereof readable against a calibrated voltage scale 57 on the instrument and provided adjacent its other end with a contact element 58 movable with the needle 56, under the influence of voltage changes on the line side of the regulator, and adapted to establish selective electrical contact with adjustable low and high limit contacts 59 and 60, respectively, built into the contact making voltmeter 51. The adjustability of the limit contacts 59 and 60 serves to provide a simple and effective way of making individual adjustments of the contacts to set the low and high limits and the permissible voltage fluctuation range beyond which the contact making voltmeter 51 functions to effect automatic voltage compensation by energizing the control circuit and setting the driving means 13 in motion to effect the change of position of the switch 11 in accordance with the demands made on the voltmeter 51 by reason of a fluctuation of voltage on the load side of the regulator which has exceeded the permissible range of voltage variation.

The main circuit of the regulator includes a power line 61 connected with the power line contacts 27 and 28 of the switch 11 which contacts are selectively connected with the coil contacts 29 and 30 through the bridging contacts 25 and 26 carried by the switch arm 22. The coil tap contact 29 is connected by a lead wire 62 to a tap on the coil 17 at the juncture of the shunt and series windings 18 and 19, respectively. The other end of the series winding 19 is connected to a load line 63; while the other end of the shunt winding 18 is grounded. One end of the control winding 20 is grounded while its other end is connected by a lead 64 to a fuse 65 and a branch lead 66 to one end of the magnetic field winding 40 of the shaded pole motor 39 while the other end of the winding 40 is grounded. With the switch 11 in the position shown in the schematic drawing, which is the boost position, the series or booster winding 19 of the coil 17 is thrown into the circuit between the power line 61 and the load line 63 to effect the desired boost in load line voltage. When the switch 11 is snapped to its other position, the current from the power line contact 28 flows through the bridging contacts 25 and 26 to the coil tap contact 30 and thence directly to the load line 63 through a lead 67. The position of the switch 11, just described, is a neutral one in which the series or booster winding 19 of the coil 17 is not connected in the circuit between the power line 61 and the load line 63. It should be noted, at this time, that a resistor device 68 is connected across the incoming power line 61 and the load line 63. This resistor device 68 has a voltage sensitive characteristic which provides surge protection to the series winding 19 of the coil 17 and also serves to maintain continuity of current flow between the power line 61 and the load line 63 during the substantially instantaneous period of break in the switch circuit while the switch arm 22 is traveling from one position to another.

The control circuit for the regulator is fed from current induced in the control winding 20 of the coil 17 through a branch lead 69 connected to the lead 66 where the fuse 65 provides protection for the control device 15 and the associated control circuit. The branch lead 69 carries current to the primary winding 52 of

the voltmeter 51. The circuit through the primary winding 52 is completed by grounding the other end of the winding. The control current from the primary winding 52 is induced into the secondary winding 53 which tends to rotate the shaft 55 through the action of the heater 54 to cause the needle 56 to be deflected thus moving the contact 58 toward either the low limit contact 59 or the high limit contact 60, in accordance with the trend of the fluctuation of voltage on the load side of the regulator. The high limit contact 60 of the voltmeter 51 is connected through a lead 70 to one contact of a two pole three position selector switch 71, shown in automatic control position in the diagram; the other two positions of the selector switch are a fixed boost position or a fixed neutral position. With the selector switch 71 in the automatic control position, the lead 70 is connected to a lead 72, through one of the switch poles, which in turn is connected to the shading pole winding 41; the current for which is induced from the alternating field of the motor 39; and also to a contact 73 of a neutralizing switch 74, and to a fixed contact 75 of a normally open limit switch 76, the blade of which is grounded. The low limit contact 59 of the voltmeter 51 is connected through a lead 77 to a contact of the selector switch 71 disposed opposite to the contact with which the lead 70 is connected. The lead 77 is connected to a lead 78, through the other of the switch poles, which lead is in turn connected to the shading pole winding 42 of the motor 39, and to a fixed contact 79 of the neutralizing switch 74 and also to a fixed contact 80 of a normally open limit switch 81, the blade of which is grounded. Both low and high limit contact circuits are completed selectively through the movement of the neutralizing switch operating cam 50 which is fixedly mounted on the drive shaft 34 which effects movement of the driving arm 33 of the switch operating member 12. When the cam 50 moves in a counter-clockwise direction it urges the spring biased blade of the neutralizing switch 74 upwardly to move a contact 82 carried by the blade into contact with the fixed contact 79 on the lead 78 to close the circuit in the shading pole winding 42 and introduce into the circuit a resistance 83 the ends of which are connected respectively with the switch blade of the neutralizing switch 74 and the ground. When the cam 50 moves in a clockwise direction it permits the spring biased blade of the neutralizing switch 74 to move downwardly to close an electrical connection between the contact 82 and the fixed contact 73 on the lead 72 to introduce the resistance 83 into the circuit of the shading pole winding 41. The amount of rotation of the operating arm 22 of the switch 11 is limited in both directions of travel by the action of the limit switch operating arm 49 which is also secured to the driving shaft 34. Movement of the switch operating arm 22 in a counter-clockwise direction is terminated when the arm 49 closes the normally open limit switch 76 and in like manner, clockwise movement of the operating arm 22 is terminated when the arm 49 effects the closing of the normally open limit switch 81. The control circuit is completed by the inclusion of an arc suppressor 84 between the leads 72 and 78 for the purpose of insuring long life for the contacts of the voltmeter 51.

With the foregoing description of the several

operating parts of the line voltage regulator completed and the main and control circuits set up, a discussion of the automatic operation of the device will serve to illustrate its effectiveness in maintaining voltage on the load line side of the regulator within the predetermined and permissible limits designated by the adjustably fixed positioning of the low and high contacts 59 and 60, respectively, of the contact making voltmeter 51. With the regulator connected between the power line 61 and the load line 63 and the several elements of the regulator positioned and connected in the manner shown in the schematic diagram, the regulator is ready to function to maintain the voltage on the load side of the regulator within the desired predetermined limits as set by the adjustment of the high and low limit contacts 60 and 59, respectively, of the contact making voltmeter 51. As the voltage on the load side of the regulator varies up and down, a corresponding change is induced in the control winding 20 of the coil 17 which impresses this proportionate voltage on the contact making voltmeter 51 through the protective fuse 65 and the lead 69 causing upward or downward deflection of the needle 56 which carries the contact 58 of the voltmeter 51. The current induced in the control winding 20 of the coil 17 also energizes the magnetic field winding 40 of the motor 39 through the fuse 65 and the lead 66. As long as the voltage on the load side of the regulator is maintained within the limits set by the position of the contacts 59 and 60 of the voltmeter 51, the motor 39 will remain at rest with the switch operating arm 33 and its associated control elements, the limit switch operating arm 49 and the neutralizing switch operating cam 50, being retained in inactive positions. Should the voltage in the circuit on the load side of the regulator rise above the high limit voltage set by the adjustment of the contact 60 and persist above the high limit for a period of time greater than the time delay factor built into the contact making voltmeter 51, which time delay is of approximately one minute in duration and serves to slow down the movement of the indicating and operating arm or needle 56 of the voltmeter 51, to eliminate many undesirable contact operations which occur in other types of meters not so equipped, the contact 58 of the voltmeter will establish contact with the high limit contact 60 to complete the circuit through the shading pole winding 41 and initiate the counter-clockwise rotation of the armature 43 of the motor 39. The counter-clockwise rotation of the motor transmits a counter-clockwise movement to the switch operating arm 33 through the medium of the time delay mechanism 14 in the form of a speed reducing gear train comprising gears 45, 46, 47 and 48 interposed between the armature shaft 44 and the shaft 34 on which the switch operating arm 33 and the limit switch operating arm 49 and the neutralizing switch operating cam 50 are mounted. The gear reduction of the time delay mechanism 14 is so constructed that a period of approximately two minutes of continued rotation of the armature 43 is required to cause the switch operating arm 33 to traverse the required distance, in a counter-clockwise direction, to effect the actuation of the switch 11 by throwing the tension spring 32, which connects the switch operating arm 33 and the arm 22 of the switch 11, over center between the arms 22 and 33 and causing the bridging contacts 25 and 28 to break connection be-

the cam 50 which permits the spring biased blade of the neutralizing switch 74 to move downwardly to break the circuit made between the contacts 79 and 82.

Let us assume now that the switch 11 is in neutral position and that the voltage in the line on the load side of the regulator has dropped below the low limit established by the positioning of the low limit contact 59 of the contact making voltmeter 51. This persisting condition of lowered voltage on the load line side of the regulator induces a corresponding change in the current induced in the control winding 20 of the coil 17 which in turn is transmitted to the voltmeter 51 causing the indicator and contact needle 56 to be deflected to the left, with reference to the schematic diagram, to a position in which the contact 58 on the needle 56 engages the high limit contact 60 of the voltmeter 51 thus closing the portion of the control circuit which energizes the shading pole winding 42 of the motor 39 to induce a clockwise rotation of the armature 43 of the motor and cause the switch operating arm 33, the limit switch operating arm 49 and the neutralizing switch operating cam 50 to move in a clockwise direction from their inactive or rest positions. The clockwise movement of the switch operating arm 33 carries the tension spring 32 to an over-center position in which it effects the snap action of the switch arm 22 from its neutral contact position to its boost position, wherein the series or booster winding 19 of the coil 17 is connected in series between the power line 61 and the load line 63 to cause the winding 19 to effect a boost action upon the voltage of the load line 63. In conformity with the manner previously described, the initial clockwise movement of the neutralizing switch cam 50 causes the closing of the contacts 73 and 82 of the neutralizing switch 74 to energize the shading pole winding 41 and place the resistance 83 in the circuit thus closed to produce a torque equal to one-half of the rated torque of the armature 43 which tends to rotate the armature in a counter-clockwise direction; however, with the contacts 58 and 59 of the voltmeter 51 closed the shading pole winding 42 of the motor 39 causes a full rated torque on the armature which overcomes the half rated torque set up by the shading pole winding 41 with the result that the armature turns in a clockwise direction to effect the desired movement of the switch operating arm 33. This clockwise motion of the shaft 34 and its associated parts continues until such time that the limit switch operating arm 49 engages and closes the normally open contacts of the limit switch 81, which action results in the shorting out of the shading pole winding 42 to stop further travel of the switch operating arm 33 in a clockwise direction. This condition persists so long as the voltmeter contacts 58 and 59 remain closed. When the voltage on the load side of the regulator has risen a sufficient amount, the contacts 58 and 59 are separated under the action of movement of the needle 56 of the voltmeter 51. The breaking of this circuit, by separating the contacts 58 and 59, permits the energized shading pole winding 41 to become effective to return the switch operating arm 33 to its rest position under the influence of the counter-clockwise rotation of the armature 43 in response to the induced current in the shading pole winding 41 which action is terminated by the breaking of the circuit in the shading pole winding 41 through the lifting action of the cam 50

on the blade of the neutralizing switch 74 to separate the contacts 73 and 82.

All of the foregoing description of the automatic operation of the line voltage regulator has been predicated on two premises; the first being that the duration of the excessive voltage fluctuation on the line side of the regulator has persisted in one and the same direction for a period of time great enough to effect the over-damped movement of the indicating and contact making needle 56 through the distance of travel necessary for it to establish contact of its contact 58 with one or the other of the adjustably positioned contacts 59 and 60 of the contact making voltmeter 51; and the other premise is that the established demand of the load line voltage must continue to persist in the established direction for the period of time delay built into the time delay mechanism 14 in order to effect the completion of an operating cycle to shift the position of the switch 11 from its previously established position to its other position to satisfy the demands of the contact making voltmeter or control device 15.

In the absence of the first mentioned time requirement, that being the one sufficient to establish the control contact within the voltmeter 51, there will be no effect upon the operating mechanism of the regulator. In the event that the elapsed time of the voltage change requirement after the establishment of the control contact within the voltmeter 51 has been made is less than the time delay period of the time delay mechanism 14, the breaking of the established contacts of the voltmeter 51 will cause the mechanism to return to its rest position without effecting a shift of position of the switch 11.

In the event that the voltage requirement of the load line circuit is not satisfied when the regulator is in boost position and the voltage requirement continues to persist, the device will remain in boost position without detrimental effect upon the operating mechanism due to the presence and function of the limit switch in the control circuit which becomes effective to stop the movement of the switch operating arm 33 when the limit switch closes.

In some instances where this condition of unsatisfied voltage requirements persist, when the regulator is retained in boost position appears with undesired frequency, it is possible to install a second voltage regulator in the line, in cascade relationship with the first regulator, to alleviate this condition.

From the foregoing description of the illustrative embodiment of the present invention, it will be apparent that a new and improved line voltage regulator has been provided which functions automatically to maintain the voltage on the load line side of the regulator within the predetermined and permissible limits as set by the adjusted positioning of contacts on a voltage responsive control device.

It should be noted that the line voltage regulator of the present invention provides a new and improved device which is of low cost design, compact construction and assembled in a manner which makes it readily accessible for inspection, adjustment, repair or even replacement if necessary of unitary portions of the regulator. The entire assembly is relatively light in weight and adapted for pole mounting with special provision being made for positioning the control device either on the exterior wall of the enclosure tank or remote therefrom as at the base of the mount-

ing pole to render the control device accessible for inspection or adjustment without the necessity of leaving the ground.

While the step type line voltage regulator of the present invention has been described in considerable detail in the foregoing specification, it is to be understood that various changes may be made in its embodiment without departing from or sacrificing any of the advantages hereinafter claimed.

I claim:

1. A step type line voltage regulator comprising a unitary core and coil structure, said coil including shunt and series windings in fixed autotransformer relationship, and a control winding, said coil windings providing a constant ratio of transformation between the load side voltage and said control winding, a power line contact, a plurality of coil tap contacts, a switch movable to selectively connect said power line and coil contacts, a multiple position switch operating member having a neutral position and a pair of switch operating positions, driving means for said switch operating member including time delay means, a voltage sensitive control device responsive to excessive voltage fluctuation on the load line to energize said driving means to move said switch operating member only upon the persistence of the excessive voltage fluctuation for a period of time not less than that required for the operation of said time delay means in one direction from its neutral position upon an excessive drop in control voltage and in the opposite direction upon an excessive rise in control voltage, and an auxiliary driving means operative to return said switch operating member to its neutral position upon completion of any change of position of said switch.

2. A step type line voltage regulator comprising a unitary core and coil structure, said coil including shunt, series and control windings in fixed autotransformer relationship and providing a constant ratio of transformation between the load line voltage and said control winding, a power line contact, a plurality of coil tap contacts, a switch movable to selectively connect said power line and coil tap contacts, a switch operating member having neutral and operating positions, driving means for said switch operating member including time delay means, and a voltage sensitive control device responsive to voltage fluctuation beyond predetermined limits in said control winding to energize said driving means to shift the position of said switch through the medium of said operating member upon the persistence of said excessive voltage fluctuation to maintain the load line voltage within the predetermined limits of fluctuation, said time delay means insuring the necessity of a persisting demand of said control device for a period of time not less than that required for the operation of said time delay means prior to the changing of said switch position.

3. The combination with a step type line voltage regulator including a unitary core and coil structure, said coil having shunt, series and control windings in fixed autotransformer relationship and providing a constant ratio of transformation between the load line voltage and said control winding, a power line contact, a plurality of coil tap contacts, a switch movable to selectively connect said power line and coil tap contacts, a switch operating member having neutral and switch operating positions, driving means for moving said switch operating member, and

time delay means in said driving means, of a control circuit for said regulator, said control circuit including a contact making voltmeter energized from current induced in said control

5 winding, said contact making voltmeter being responsive to excessive fluctuation of voltage in the load line to energize said driving means to shift the position of said switch only upon the persistence of the excessive voltage fluctuation for a period of time not less than that required for the operation of said time delay means to selectively insert said series winding of said coil in the circuit between the power and load lines to increase the load line voltage in response to an excessive drop in the load line voltage or to remove the series winding from its boosting connection in response to an excessive rise in load line voltage.

4. The combination with a step type line voltage regulator including a unitary core and coil structure, said coil having shunt, series and control windings in fixed autotransformer relationship and providing a constant ratio of transformation between the load line voltage and said control winding, a power line contact, a plurality of coil tap contacts, a switch movable to selectively connect said power line and coil tap contacts, a switch operating member having neutral and switch operating positions, driving means for moving said switch operating member, and time delay means in said driving means of a control circuit for said regulator, said control circuit including a contact making voltmeter energized from current induced in said control winding, said contact making voltmeter being responsive to excessive fluctuation of voltage in the load line to establish a control contact and energize said driving means to shift to position of said switch through the medium of said operating member only upon the persistence of the excessive voltage fluctuation for a period of time not less than that required for the operation of said time delay means to maintain the load line voltage within predetermined limits of fluctuation by selectively inserting or cutting out said series winding of said coil in the circuit between the power and load lines

45 to increase the load line voltage in response to an excessive drop or decrease the load line voltage in response to an excessive rise, whereby the load line voltage is maintained automatically within predetermined and permissible limits of fluctuation.

5. The combination with a step type line voltage regulator including a unitary core and coil structure, said coil having shunt, series and control windings in fixed autotransformer relationship and providing a constant ratio of transformation between the load line voltage and said control winding, a power line contact, a plurality of coil tap contacts, a switch movable to selectively connect said power line and coil tap contacts, a switch operating member having neutral and operating positions, and a shaded pole motor for driving said switch operating member, of a control circuit for the regulator, said control circuit including a voltage sensitive control device energized from current induced in said control winding of said coil, said voltage sensitive device being responsive to excessive fluctuation in the load line to establish a control contact and energize said shaded pole motor to change the position of said switch through the medium of said switch operating member to selectively insert said series winding of said coil in the circuit between the power line and said load line to increase the load line voltage in response to an excessive drop

in control winding voltage or to cut out said series winding from between the power and load lines to decrease the load line voltage in response to an excessive rise in said control winding voltage, whereby the load line voltage is maintained automatically within predetermined and permissible limits of fluctuation.

6. The combination with a step type line voltage regulator including a unitary core and coil structure, said coil having shunt, series and control windings in fixed autotransformer relationship and providing a constant ratio of transformation between the load line voltage and said control winding, a power line contact, a plurality of coil tap contacts, a switch movable to selectively connect said power line and coil tap contacts, a switch operating member having a neutral and switch operating position, driving means for moving said switch operating member from neutral to an operating position, and driving means for returning said switch operating member to neutral position upon completion of a change of position of said switch, of a control circuit for said regulator, said control circuit including a contact making voltmeter energized from current induced in said control winding, said contact making voltmeter being responsive to excessive fluctuations of voltage in the load line to establish a control contact and energize said driving means to move said switch operating member in one direction from its neutral position upon an excessive drop in load line voltage to shift the position of said switch and thereby insert said series winding of said coil into the circuit between the power and load lines to increase the load line voltage and move said switch operating member in the opposite direction from its neutral position upon an excessive rise in load line voltage to shift the position of said switch and thereby remove said series winding from the circuit between the power line and load line to decrease the load line voltage, and control means responsive at the completion of a shift of position of said switch to energize said driving means for returning said switch operating member to its neutral position.

7. The combination with a step type line voltage regulator including a unitary core and coil structure, said coil having shunt, series and control windings in fixed autotransformer relationship and providing a constant ratio of transformation between the load line voltage and said control winding, a power line contact, a plurality of coil tap contacts, a switch movable to selectively connect said power line and coil tap contacts, a switch operating member having neutral and switch operating positions, a shaded pole motor for driving said switch operating member from neutral to an operating position, and a pole shading winding for returning said switch operating member to neutral position upon completion of a change of position of said switch, of a control circuit for the regulator, said control circuit including a contact making voltmeter energized from current induced in said control windings of said coil, said contact making voltmeter being responsive to excessive fluctuation of voltage in the load line to establish a control contact to energize said shaded pole motor to shift the position of said switch through the

medium of said switch operating member to maintain the load line voltage within predetermined limits of fluctuation by selectively inserting or cutting out said series winding of said coil

5 in the circuit between the power line and load line to increase the load line voltage in response to an excessive drop or decrease the load line voltage in response to an excessive rise, and control means responsive at the completion of a shift of position of said switch to energize said pole shading winding for returning said switch operating member to its neutral position.

8. The combination with a step type line voltage regulator comprising a core and coil structure, a power line contact, a plurality of coil tap contacts, a switch movable to selectively connect said power line and coil tap contacts, a switch operating member having neutral and operating positions, driving means for said switch operating member including time delay means, and a potential transformer, of a control circuit for the regulator, said control circuit being energized by said potential transformer and including a voltage sensitive control device operative in re-

15 sponse to excessive voltage fluctuation in the load line to energize said driving means to shift the position of said switch through the medium of said switch operating member, said time delay means in said driving means serving to insure the 20 shifting of said switch only upon the persistent excessive voltage fluctuation for a period of time equal to that of the time delay means.

9. In a step type line voltage regulator the combination of a unitary core and coil structure, said

35 coil having shunt and series windings in fixed autotransformer relationship, and a control winding, said coil windings providing a constant ratio of transformation between the load line voltage and said control winding, a power line

40 contact, a plurality of coil tap contacts, a switch movable to selectively connect said power line and said coil tap contacts, operating means for said switch, including driving means incorporating a time delay means, and control means responsive at

45 to persisting excessive voltage fluctuation in the load line to energize said switch operating means to shift the position of said switch only upon the persistence of the excessive voltage fluctuation for a period of time not less than that required 50 for the operation of said time delay means to selectively place said series winding of said coil into the circuit between the power and load lines in response to an excessive drop in load line voltage or to remove said series winding from the 55 last mentioned circuit in response to an excessive rise in load line voltage to thereby automatically maintain the load line voltage within predetermined limits of fluctuation.
